RHEOSTAT WITH MAGNETIC OPERATOR

Pedro S. Ramos, Chicago, Ill., assignor to Electra
Voice Corporation, Chicago, Ill., a corporation
of Delaware

Application May 17, 1946, Serial No. 670,319

11 Claims. (Cl. 201—56)

1

The present invention relates in general to sealed electrical apparatus, and has more particular reference to current flow equipment, including adjustable devices such as switches, resistance units, and the like.

An important object of the present invention is to provide an electrical current flow controlling device, including adjustably movable elements enclosed in a sealed envelope, with connecting means extending outwardly of the envelope for connecting the adjustable elements in external electrical circuits, devices embodying the present invention having associated means disposed outwardly of, and preferably mounted on, the envelope, and operable, outwardly of the envelope, to effect adjusting movement of the envelope enclosed elements of the device.

Another important object is to provide devices, including envelope enclosed elements adapted for relative adjustment within the envelope, in combination with adjusting means mechanically disconnected from said adjustable elements and disposed entirely outside of the envelope, yet operable, outwardly of the envelope, to induce adjusting movement of the adjustable elements; a further object being to induce such adjusting movement of the elements by electromagnetic action, accomplished through the walls of the enclosing envelope means.

Another important object is to provide a flow control unit comprising relatively adjustable elements sealed within an enclosing envelope of non-magnetic material, such as glass, and to provide for the relative adjusting movement of said elements from outwardly of the envelope by mounting magnetic means on at least one of the elements, whereby said element may be moved within the envelope in response to the movement of cooperating magnetic means disposed entirely outside of the envelope.

Another important object is to provide an electrical resistance unit, such as a rheostat or potentiometer, enclosed in an envelope of non-magnetic material, and including a movable resistance adjusting element within the envelope and carrying magnetic means on such movable element, in combination with movable means mounted outwardly of the envelope and carrying magnetic means in position to move in a path registering with the path of movement of the magnetic means within the envelope, whereby adjusting movement of the magnetic means, outwardly of the envelope, may result in the adjustment of the movable element within the envelope.

Another important object is to provide sealed

2

means of the character mentioned that will perform its circuit controlling function regardless of surrounding moisture, the electrical characteristics of devices embodying the present invention remaining constant throughout the service life of the device, regardless of surrounding atmospheric conditions. As a consequence, adjustable resistance units and other devices embodying the present invention may be successfully used in radio, electronic, and other electrical apparatus, under conditions which seriously impair the operating characteristics of circuit control devices of the sort heretofore provided, the operating elements of which are exposed to the surrounding atmosphere.

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a sectional view through a resistance unit embodying the present invention;

Fig. 2 is a sectional view taken substantially along the line 2—2 in Fig. 1;

Fig. 3 is a perspective view of a mounting bracket forming a part of the unit shown in Fig. 30 1; and

Fig. 4 is a sectional view taken substantially along the line 4—4 in Fig. 1.

To illustrate the invention, the drawings show an electrical circuit controlling device, comprising a pair of relatively movable elements 11 and 12 sealed within an envelope 13, and means 14 mounted and disposed outwardly of the envelope and operable to accomplish relative movement of the elements 11 and 12.

40 To this end, the envelope 13 comprises non-magnetic material, such as glass, although other non-magnetic material may, of course, be employed. To accomplish relative movement of the elements 11 and 12 within the envelope, one of 45 said elements, such as the element 11, may be anchored against movement in the envelope, while the other element, as the element 12, may be movably supported within the envelope. Magnetic means, such as a permanent magnet 15, may be mounted in any suitable or preferred fashion on the member 12, and supported in position thereon to move with the element 12 in a path immediately within a wall 16 of the envelope. The adjusting means 14 may comprise a 50 support member 17 carrying magnetic means,

such as a permanent magnet 18, for movement in a path corresponding with the path of movement of the magnet 15, the magnets 15 and 18 being disposed with facing ends on opposite sides of the envelope wall portion 16. When the member 17 is moved outwardly of the envelope, a corresponding movement of the arm 12 will be accomplished within the envelope, by virtue of the magnetic connection through the envelope wall 16 between the magnets 15 and 18.

As a consequence of the foregoing arrangement, the elements 11 and 12 may be relatively adjusted from outwardly of the envelope, while remaining at all times, during the service life of the unit, entirely sealed and protected from the surrounding atmosphere. The envelope 13 preferably comprises an hermetic seal around the enclosed elements 11 and 12. If desired, the envelope may be evacuated, or may be filled with a suitable inert gas, for the protection of the enclosed elements. In any event, the sealed elements are adapted to maintain predetermined electrical characteristics thereof substantially unchanged throughout the service life of the unit.

As shown, the envelope 13 preferably comprises a cup-shaped base 19 and a cover member 20, forming the envelope wall 16. The cover 20 may be provided with annularly flanged marginal portions 21, sized to fit within the open end of the cup-shaped base 19 and sealed in place. The base and cover may conveniently be made of glass, and may be sealed together by usual glass sealing methods after the elements 11 and 12 have been assembled therein.

The elements 11 and 12 may be supported within the envelope 13 in any convenient or preferred fashion. As shown, the members are mounted on a support pedestal 22. This pedestal preferably is mounted centrally within the envelope, and comprises a base portion 23 sealed in and supported by the bottom wall of the cup-shaped base 19. To this end, the base portion 23 may comprise a metal adapted to seal with the glass material of the base 19. A conductor wire 24 of metal, also preferably sealable to glass, is electrically connected to the base portion 23 and extends thence outwardly of the envelope through a glass-to-metal seal 25 in the base 19. The base portion 23 may include a projecting stem, comprising a spindle portion 26 and a threaded portion or stud 27. The element 12 preferably comprises a resilient strip forming an arm at one end for rotational engagement on the spindle portion 26, whereby said arm may extend radially outwardly of the pedestal 22 and rotate about the axis of said pedestal. The element 12 is secured on the spindle portion 26 by a pedestal extension 28, having an internally threaded socket for receiving the threaded spindle portion 27. If desired, a spring washer 29 may be held on the spindle portion 26 with the pivoted end of the arm 12, by the pedestal extension 28 operating as a holding nut, when assembled in position on the stud 27.

The pedestal portion 28, when in mounted position on the stud 27, has a stud remote end in position to engage and support the inner face of the cover member 20, said end being preferably formed with a seat 30 for receiving a mounting bracket 31, said mounting bracket being secured to the pedestal in the seat 30 in any suitable fashion, as by means of the diametral pin 32. The bracket 31 has a pair of arms 33 extending outwardly of the pedestal, and having

ends in position to supportingly engage the element 11 in order to support said ends on the pedestal 22.

The element 11, in the illustrated embodiment, 5 comprises a resistance unit of any preferred character, as, for example, a curved strip 34 of insulating material secured at its opposite ends on the arms 33, and having a resistance conductor 35 mounted on the strip in helically wound coils. The resistance conductor, however, may take any preferred form and may be mounted on, or in, the support strip 34 in any suitable manner; for example, the strip 34 may itself 10 comprise resistance material, in which case suitable insulation should be provided between the opposite ends of the strip 34 and the mounting pedestal 22, to prevent the electrical connection of the resistance element with the pedestal through the bracket 31. The opposite ends of 15 the resistance means 35, whether a resistance wire wound on the strip 34, or whether the same 20 comprises resistance material incorporated in the strip 34, are electrically connected, as by connecting elements 36, with conductors 37 extending outwardly of the envelope, as through 25 glass-to-metal seals 38 formed in the walls of the envelope.

When mounted in the envelope, the end of the element 12 remote from the pedestal 22 makes 30 yielding contact with the resistance means 35, as at and along an edge of the curved strip 34, the resilience of the arms 12 serving to press its pedestal remote end upon the element 11. The magnet 15 may comprise a small horseshoe 35 magnet anchored by support lugs 39 on the arm 12 immediately within the resistance element 11, the bracket 39 serving to support the magnet 40 immediately within the envelope wall 16, whereby the arm 12 may be turned about the axis of the pedestal 22, from one end of the resistance element 11 to the other end thereof, by magnetic action exerted upon the magnet 15 through the overlying envelope wall 16.

After the elements 11 and 12 have been mounted 45 in the base 19, as aforesaid, the cover 20 may be applied within the open end of the cup-shaped base, the flanged portions 21 of the cover snugly encircling the resistance element 11 and aiding in supporting the same in position within the 50 envelope. After the cover has been so assembled, it may be sealed to the cup-shaped base in any preferred fashion, whereby the enclosed elements 11 and 12 are hermetically enclosed and isolated from the surrounding atmosphere.

Any suitable arrangement may be employed 55 for mounting the actuating magnet 18 in position to move the magnet 15 within the envelope. As shown, the magnet 18 may comprise a horseshoe magnet mounted by lugs on the bracket 17, comprising an arm mounted for rotation, outwardly 60 of the envelope, about the axis of the pedestal 22, whereby the magnet 18 is guided to move in a track across the envelope wall 16, immediately outwardly thereof and registering with the path 65 of movement of the magnet 15 within the envelope. To this end, the supporting means 14 may comprise a bracket having arms 40 for mounting the same on the envelope 13, said arms having terminal lugs 41 adapted to engage in seats 42 formed in the outer surfaces of the envelope, as on the bottom of the base 19. The arms 40, inwardly of the lugs 41, are adapted 70 to seat in grooves 43 formed in the side walls of the base; and the arms may be formed with inwardly struck lugs 44, in position to engage the

envelope, as at the edges of the cover means 20, whereby the bracket is held on the envelope by and between the lugs 41 and 44. The bracket may, also, include a central portion 45 formed with an opening 46, in which is mounted a support bushing 47 carrying a turnable spindle 48, the magnet carrying arm 17 being attached, as at one end of the spindle 48. A suitable operating handle or knob may be secured to the spindle 48, at the end thereof remote from the arm 17, in order to facilitate the turning of the spindle in order, thus, to move the arm 17.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. An adjustable electrical unit comprising sealed envelope means, a pair of elements mounted within the envelope, one of said elements comprising an arm supported for relative swinging movement with respect to the other element and having a portion adapted to electrically engage said other element, inner magnetic means connected with said arm and supported thereby in position to move adjacent a wall portion of said envelope, said wall portion comprising non-magnetic material, and outer magnetic means mounted outwardly of said envelope and movable adjacent said wall portion, whereby to adjustably shift said movable element by magnetic action exerted through said envelope wall portion between said inner and outer magnetic means.

2. An adjustable electrical unit comprising an envelope, a pair of elements mounted within the envelope, one of said elements comprising an arm supported for relative swinging movement with respect to the other element and having a portion adapted to electrically engage said other element, inner magnetic means connected with said arm and supported thereby in position to move adjacent, and movable in a path extending across, a flat wall portion of said envelope, said wall portion comprising non-magnetic material, and outer magnetic means mounted outwardly of said envelope and movable adjacent said wall portion, in a path registering with the path of said inner magnetic means, whereby to adjustably shift said movable element by magnetic action exerted through said envelope wall portion between said inner and outer magnetic means.

3. An adjustable electrical unit comprising an envelope, a pair of elements mounted within the envelope, one of said elements comprising an arm, pivotally supported for relative swinging movement with respect to the other element, about a pivot axis, and having a portion adapted to electrically engage said other element, inner magnetic means connected with said arm and supported thereby in position to move in an arcuate path adjacent a wall portion of said envelope, said wall portion comprising non-magnetic material, and outer magnetic means mounted outwardly of said envelope and movable in an arcuate path adjacent said wall portion, and in registration with the arcuate path of said inner magnetic means, whereby to adjustably shift said movable element by magnetic action exerted

through said envelope wall portion between said inner and outer magnetic means.

4. An adjustable electrical unit comprising an envelope, a pair of elements mounted within the envelope, one of said elements comprising a movable member adapted to shift with respect to the other element, magnetic means connected with one of said elements and supported in position to move adjacent a wall portion of said envelope, said wall portion comprising glass, magnetic means and means to pivotally mount the same for movement, outwardly of said envelope, in an arcuate path adjacent said wall portion, whereby to adjustably shift said movable element by magnetic action exerted through said envelope wall portion between said inner and outer magnetic means.

5. An adjustable electrical unit comprising an envelope of glass, a pair of elements mounted within the envelope, one of said elements comprising a movable member adapted to shift with respect to the other element, inner magnetic means connected with one of said elements and supported in position to move adjacent a flat non-magnetic wall portion of said envelope, outer magnetic means and means to mount the same for turning movement about a pivot axis, outwardly of said envelope, in position to move across said flat wall portion, in spaced registration with said inner magnetic means, whereby to adjustably shift said movable element by magnetic action exerted through said envelope wall portion between said inner and outer magnetic means.

6. An adjustable electrical unit comprising an envelope, a pair of elements mounted within the envelope, one of said elements comprising an arm supported for pivotal movement with respect to said other element, inner magnetic means mounted on said arm in position to move in an arcuate path of movement adjacent a wall portion of said envelope, said wall portion comprising non-magnetic material, and outer magnetic means mounted outwardly of said envelope and movable in an arcuate path registering with the arcuate path of movement of the other inner magnetic means adjacent said wall portion, whereby to adjustably shift said movable element by magnetic action exerted through said envelope wall portion between said inner and outer magnetic means.

7. An adjustable electrical unit comprising an envelope, a pair of elements mounted within the envelope, one of said elements comprising an arcuate resistor, and the other element comprising an adjustable resistor contacting arm mounted for swinging movement on a pivot axis, inner magnetic means connected to said contacting arm in position to move adjacent a wall portion of said envelope in an arcuate path centered on said axis, said wall portion comprising non-magnetic material, and outer magnetic means pivotally mounted outwardly of said envelope and movable adjacent said wall portion in an arcuate path registering with the path of movement of said inner magnetic means, whereby to adjustably shift said contacting member by magnetic action exerted through said envelope wall portion between said inner and outer magnetic means.

8. An adjustable electrical unit comprising an envelope, a central support providing a pivot axis in said envelope, a pair of relatively adjustable elements mounted within the envelope, one of said elements comprising an elongated member, disposed circularly about said central support,

and the other element comprising an arm pivoted on said support in position to move along the elongated member, inner magnetic means connected with said arm in position to move therewith adjacent a wall portion of said envelope, said wall portion comprising non-magnetic material, and outer magnetic means mounted outwardly of said envelope for movement adjacent said wall portion in a circular path about said pivot axis, whereby to adjustably shift said movable element on said support by magnetic action exerted through said envelope wall portion between said inner and outer magnetic means.

9. An adjustable electrical unit comprising an envelope having a cylindrical wall and a flat end wall, a pair of relatively adjustable elements mounted within the envelope, one of said elements comprising an arcuate member supported within and by a portion of said cylindrical wall, the other of said elements comprising a pivoted member mounted for rotation about a pivot axis on which said arcuate member is centered, inner magnetic means connected with said pivoted member in position to move in a circular path adjacent said flat end wall of said envelope, said end wall comprising non-magnetic material, and outer magnetic means mounted outwardly of said envelope and movable in a circular path adjacent said end wall, whereby to adjustably shift said movable element by magnetic action exerted through said end wall between said inner and outer magnetic means.

10. An adjustable electrical unit comprising an envelope formed in sections, one section comprising an open ended cylindrical casing and another section forming a flat end closure for the casing, a pair of elements mounted on one of said sections and enclosed within the envelope by the other section, one of said elements comprising an arm pivoted for turning movement within the cylindrical casing about the central axis thereof, inner magnetic means connected with said arm in position to move within and adja-

cent said end closure, said closure comprising non-magnetic material, and outer magnetic means mounted outwardly of said envelope and movable adjacent said end closure, whereby to adjustably shift said arm by magnetic action exerted through said cover closure between said inner and outer magnetic means.

11. An adjustable electrical unit comprising an envelope formed in sections, one section comprising an open ended casing having a cylindrical side wall and another section comprising non-magnetic material forming a flat end closure for the casing, a central support mounted in said envelope and providing a pivot axis substantially in alignment with the axis of said cylindrical casing, a pair of elements mounted in said envelope, one of said elements comprising an arcuate resistor supported within the cylindrical wall of said casing, the other of said elements comprising an arm pivoted on said support and having a support remote portion adapted to electrically engage and ride upon said resistor, an inner magnet secured on said arm in position to move therewith adjacent and within said end closure, in an arcuate path centered on said pivot axis, an outer magnet, and means to support the same on said envelope and outwardly of said end closure, in position to move adjacent and outwardly of said end closure, in an arcuate path centered on said pivot axis and registering with the path of movement of said inner magnet, whereby said arm may be adjustably shifted along said resistor by magnetic action exerted through said end closure between said inner and outer magnets.
